UNITED STATES PATENT OFFICE.

CHRISTIAN F. MEYER, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

UNIVERSAL LOOP-REGULATING MECHANISM FOR FULL-FASHIONED-KNITTING MACHINES.

Application filed December 24, 1927. Serial No. 242,416.

My invention relates to full-fashioned knitting machines, and more specifically to improvements in the loop regulating mechanism thereof commonly employed in well-known 5 manner to varyingly control the lengths of loops drawn by each needle during the laying of successive courses so as to regulate their length and to compensate for the introduction to some of the needles only of an extra or reinforcing thread or yarn.

The main objects of my present invention are to provide in a minimum of space occupied for an increase in possible loop-regulating controls, to insure a more convenient and 15 positive selective control of any desired loop regulation, to permit the use of a plurality of jointly controlled regulating mechanisms advantageously spaced lengthwise of the machine so as to avoid lost motion through torsional shaft strains, and to automatically free such mechanism from acting when the cam shaft is shifted longitudinally as heretofore to bring other cams into action.

With the above objects outlined, and with 25 others that will appear as the description progresses, my invention comprises the improved construction hereinafter set forth in detail in connection with the drawings accompanying the same and forming part thereof, the novel 30 features which I desire to secure by Letters Patent being defined in the subjoined claims.

Fig. 1 indicates in a diagrammatic perspective view short portions of certain known shafts ordinarily extending the entire length 35 of a usual full-fashioned knitting machine, and the connection thereto of a usual loop-regulating control mechanism with my invention applied thereto, for the single needle bar indicated, the general structure and known 40 operation thereof being as heretofore and requiring no further showing.

Fig. 2 is a separate front elevation of my improved loop-regulating mechanism, showing a preferred embodiment thereof and sufficient 45 detail of the known machine structure to fully disclose its application and operation.

Fig. 3 is a corresponding side elevation of the same.

The regulation of loop lengths in full fashioned knitting machines is common practice, 50 it being essential for quality and finish of the knitted product to vary their lengths even in the making of one stocking, or in a single

course thereof and more particularly when extra reenforcing thread is introduced to 55 some of the needles and not to the others; such known loop regulation being accomplished as heretofore, through the action of certain cams on needle-bar connected levers to rock said bar toward or away from the sinkers during the laying of the thread, regulation of such bar rocking movements being controlled from a regulating shaft in the manner heretofore employed and wellknown.

Fig. 1 of the drawings indicates short 65 lengths of certain known shafts of a full-fashioned knitting machine commonly extending the full length thereof and controlling in wellknown manner the loop regulating movements of the different knitting sections, 70 a single section 5 of the latter alone being indicated, it being understood, however, that certain elements are repeated as usual throughout the length of the machine and jointly function as heretofore to impart similar simultaneous movements to each knitting section. As shown, bar 5 is pivoted to a carrying arm 6 fixed on needle bar shaft 7, said bar being rockable on such pivotal support through a fixed depending arm 8 having a 80 pivotally connected bar 9 adjustably engaging a presser lever 10 secured as usual to presser shaft 11. Presser lever 10 is actuated, as heretofore, by a presser cam 12 on main cam shaft 13, and the action of said cam is modified in wellknown manner by means of a lever 14 on regulating shaft 15, said lever having a stud 16 forming a stop against which the end of lever 10 is drawn by a spring 17. As heretofore shaft 15 has been determinedly 85 rocked by additional cams on shaft 13 acting on additional fixed arms on said shaft 15 to modify the action thereon of cam 12 and impart additional rocking movements to needle bar 5 as required or desired for the purposes 90 heretofore set forth; my present invention relating to improved mechanism for determinedly and accurately oscillating or rocking said shaft 15 as will now be particularly 95 described.

The cam shaft of the usual full fashioned knitting machine has as heretofore double sets of cams, one or other of which set is brought into play by longitudinal shift of said shaft and the latter is so crowded that cams for 105 operating the regulating shaft must be dis-

- posed as space avails. In practice it is advisable to repeat such regulating cams at different portions in the length of the cam shaft so as to divide the torsional strain on the latter which may otherwise cause lost motion or deferred action along its length and consequent defective control movements; but such necessary repeats limit the variety of control cams that may be employed, and furthermore 10 require that the operator must move along the entire length of the machine in placing each one in operation, a forgotten one or a mis-set one causing defects and even serious damage.
- 15 To overcome the above disadvantages of the heretofore known control mechanism my improvements comprise the use of compound cams advantageously spaced lengthwise of the machine, jointly operated anywhere in 20 the length of the latter, and such compound cams provide for a maximum of possible control movements.

Referring now particularly to Figs. 2 and 3, which show only main cam shaft 13, regulating shaft 15, and longitudinal front beam 4, of the known knitting machine, as sufficient to disclose my improved compound cam regulating mechanism indicated in connection therewith, such compound cam, as indicated, 30 comprising a sleeve 20 having spaced end flanges 21 and 22 to the opposite peripheral faces of which may be secured segmental or full-ring cam sections as by bolts 23. Sleeve 20 may be advantageously placed and fixed 35 to cam shaft 13, and, as indicated, four different control cams, 24, 25, 26 and 27 may be secured to its flanges by said bolts 23, thus providing in compact space for four different loop control regulations. And, in order 40 that each such cam may independently function, I employ, as indicated, a regulating cam arm 30 on shaft 15 with the free end thereof preferably forked, as shown, to carry a transverse shaft 31 upon which is mounted 45 a double treaded anti-friction roller 32 slideable lengthwise on said arm shaft into the plane of any of the control cams 24, 25, 26, or 27 for action of the latter on said regulating arm 30 to oscillate or rock regulating shaft 50 15. A shifting arm 33 is provided for roller 32, and the preferred double tread of the latter shown provides for minimum longitudinal shift of said roller, one tread 32^a as will be seen acting on either cam 24 or 25, while 55 the other tread 32^b acts on cams 26 or 27.

The compound cam above set forth might in some cases have an added or additional flanges and the roller adapted to serve all, and by its use I secure in a minimum of cam shaft space occupied for a maximum of regulating control movements. Such saving in space permits me to employ more than one such cam on the cam shaft and to advantageously space them so as to avoid torsional strain on said shaft; and in order that all

may act alike, I provide a rod 35 extending along the machine in parallel relation to regulating shaft 15, said rod being suitably supported to permit longitudinal shift thereof and having the ends of each roller shift arm 70 arm 33 fixed thereto so the latter will move equally and in unison. Said shaft may be moved through a fixed notched sleeve 36, handled as shown, and slidable beneath a bearing extension arm 37 having a notch engaging pin 38 so as to indicate the set position of the roller and to retain it in such adjusted position.

When the cam shaft 13 is shifted, as before stated, to bring its set of narrowing cams into action, regulating shaft 15 is further operated thereby to rock needle bar 5 so as to release the needle loop tensions thereon and permit their transfer to other needles as heretofore; but such cam shaft shift is not sufficient to move the new compound cam with its cams 24, 25, 26, and 27 out of the broad plane of regulating arm 30, so provision must be made to free said arm from rotating with regulating shaft 15 when the cam shaft is 90 thus shifted, and to lock it to said shaft 15 so as to rotate the latter when cam shaft 13 is shifted back to again bring its regulating cams into action.

Such freeing and locking of arm 30 to shaft 15 is simply provided for, as indicated in the drawings by loosely stringing said arm on said shaft between fixed collars 40 and 41 on the latter, and providing a fixed bracket 42 mounted on front beam 4, the end 43 of said bracket, and spaced lugs 44, 44 on collar 41 having apertures alined with an aperture in arm 30 for a series of locking bolts longitudinally movable therein. Locking bolt 41^a mounted in lugs 44, 44 is adapted to slide 100 sufficiently to enter and engage the aperture in arm 30 so as to lock the latter to shaft 15, such sliding movement shifting bolt section 46 carried in said arm aperture to cause the latter to press a spring-back bolt section 47 mounted in bracket end 43 free from engagement with arm 30. When bolt 41^a is reversely moved, spring-backed bolt 47 is projected to lock arm 30 to bracket 42 thus holding it against movement when shaft 15 is rotated. Bolt 41^a may be simply shifted when cam shaft 13 is shifted, as shown, through an arm 50 on the latter secured to said bolt. 115

In operation my improved regulating mechanism functions as heretofore but in an improved and simplified manner; the operator merely having to shift rod 35 by means of handle sleeve 36 so as to definitely engage the entire series of cams desired and as indicated by the position of pin 38 in the proper notch of sleeve 36. Such movement of rod 35 positively moves each arm 33 connected to it, and each arm moves its roller 32 into the plane of the desired regulating cam which then operates as heretofore through arm 30 120 125 130

to oscillate or rock shaft 15, such movement swinging arm 14 on said shaft to position lug 16 for proper action on regulating lever 10, connected to lever bar 5 and swinging the latter as heretofore. And when cam shaft 13 is shifted, as in narrowing, arm 50 on said shaft moves bolt 41 to free arm 30 from locked position to shaft 15 to locked position to bracket 42 by advance of spring-backed bolt 47, in which position shaft 15 may be rotated without moving said arm 30.

The cams 24, 25, 26 and 27 indicated may be used for various regulating purposes, either to supplant those heretofore used in wellknown manner, or to add additional loop regulating movements to shaft 15, said cams being either sectional for action during the laying of the thread for certain needles as in partial reenforcing as well understood, or circumferential cams to act on all the needles as in making different loop lengths for heavier thread, loose courses, or the like.

The compound cams of my improvements permit of added regulating movements if desired and their compact location permit their repetition along the length of the cam shaft as desirable for accuracy and avoidance of delayed movement caused by torsional distortion of said shaft under strains resulting where only one cam is used in the length of said shaft; and the automatic freeing of the regulating arm 30 when the cam shaft is shifted permits the required movement of the latter without clashing of said arm and its actuating cams.

From the foregoing description it is believed that the nature of my invention and its operation will be readily understood, the specific showing of the drawings however being but a preferred embodiment thereof capable of modifications and changes within the spirit of my invention as defined in the following claims.

What I claim is:

1. In a full-fashioned knitting machine, a loop-regulating mechanism comprising a needle-bar, a loop-regulating shaft operatively connected to the latter, and a cam shaft; a plurality of loop-regulating cams on said cam shaft, a lever on said loop-regulating shaft operatively engageable with any of said cams, and means to selectively engage said lever with a determined cam.

2. In a full-fashioned knitting machine, a loop-regulating mechanism comprising a needle-bar, a loop-regulating shaft operatively connected to the latter, and a cam shaft; a compound cam on said shaft having a plurality of cam faces arranged in different transverse planes, a lever on said loop-regulating shaft adapted to operatively engage either of the different cam faces, and means for selectively positioning said lever to engage with a determined cam face.

3. In a full-fashioned knitting machine, a loop regulating mechanism comprising a series of needle bars, a loop regulating shaft operatively connected to each of the latter, and a cam shaft; a plurality of compound cams disposed along the length of said cam shaft and each having a plurality of similar respective cam faces arranged in different transverse planes, a plurality of levers on said loop regulating shaft, one for each compound cam, each adapted to operatively engage either of the different cam faces of its respective compound cam, and means for jointly and simultaneously positioning each respective lever to selectively engage with a determined similar cam face of its respective compound cam.

4. In a full-fashioned knitting machine, a loop regulating mechanism comprising a needle-bar, a loop-regulating shaft operatively connected to the latter, and a cam shaft; a plurality of loop-regulating cams on said cam shaft, a lever on said loop-regulating shaft having a shiftable cam-engaging member, and means to determinedly shift said member to selectively engage with any of said cams.

5. In a full-fashioned knitting machine, a loop-regulating mechanism comprising a needle-bar, a loop-regulating shaft operatively connected to the latter, and a cam shaft; a compound cam on said shaft having a plurality of cam faces arranged in different transverse planes, a lever on said loop-regulating shaft having a shiftable cam-engaging member, and means for selectively shifting said member to engage with a determined cam-face.

6. In a full-fashioned knitting machine, a loop-regulating mechanism comprising a needle-bar, a loop-regulating shaft operatively connected to the latter, and a cam shaft; a compound cam on said shaft having a plurality of cam faces adjustably fixed thereto in different transverse planes, a lever on said loop-regulating shaft having a shiftable cam-face engaging member, and means for determinedly shifting said member into the plane of a selected cam face.

7. In a full-fashioned knitting machine, a loop regulating mechanism comprising a needle-bar, a loop-regulating shaft operatively connected to the latter, and a cam shaft; a cam block on said shaft having a plurality of cam-securing radial flanges arranged in different transverse planes, cam blocks securable to said flanges in adjustable circumferential position, a lever on said loop-regulating shaft having a forked end, a shaft carried by said fork, a cam-engaging member on said shaft longitudinally shiftable thereon to engage either cam block, and a shift-rod extending lengthwise of the knitting machine and operatively engaging said member,

whereby longitudinal shift of said rod will determinedly position said member for action of a selected cam block.

8. In a full-fashioned knitting machine, a loop regulating mechanism comprising a needle-bar, a loop-regulating shaft operatively connected to the latter, and a cam shaft; a plurality of cam blocks spaced along the length of said cam shaft and fixed thereto, 10 each block having a plurality of cam-securing radial flanges arranged in different transverse planes, similar cam blocks securable to the several flanges of the respective cam blocks in adjustable circumferential position, a plurality of levers on said loop-regulating shaft, 15 one for each cam block, and each lever having a forked end carrying a transverse shaft, cam-engaging members on the respective transverse shafts operatively movable into 20 the planes of their respective cams and connected by a shift rod extending length-wise of the knitting machine, and means for determinedly shifting said rod to jointly move said cam-engaging members for action there- 23 on of similar cams of their respective cam blocks.

9. In a full-fashioned knitting machine, a loop regulating mechanism comprising a needle-bar, a loop-regulating shaft operatively connected to the latter, a longitudinally shiftable cam shaft having a loop-regulating cam fixed thereto, and a cam-actuated lever mounted on said loop-regulating shaft; said lever being rotatably locked to said loop regulating 35 shaft by longitudinal shift of the cam shaft.

10. In a full-fashioned knitting machine, a loop regulating mechanism comprising a needle-bar, a loop-regulating shaft operatively connected to the latter, a longitudinally shift- 40 able cam shaft having a loop-regulating cam fixed thereto, and a cam-actuated lever mounted on said loop-regulating shaft; means oper- 45 ated by shift of said cam shaft in one direc- tion to lock said lever to said loop-regulating shaft, and to free said lever on reverse shift of said cam shaft.

11. In a full-fashioned knitting machine, a loop regulating mechanism comprising a needle-bar, a loop-regulating shaft operatively connected to the latter, a longitudinally shift- 50 able cam shaft having a loop-regulating cam fixed thereto, and a cam-actuated lever mounted on said loop-regulating shaft; a slide bolt operated by shift of said cam shaft in one 55 direction to lock said lever to said loop-regu-

lating shaft, and to free said lever on reverse shift of said cam shaft.

12. In a full-fashioned knitting machine, a loop regulating mechanism comprising a needle-bar, a loop-regulating shaft operatively 60 connected to the latter, a longitudinally shiftable cam shaft having a loop-regulating cam fixed thereto, and a cam-actuated lever mounted on said loop-regulating shaft; a fixed member on said loop-regulating shaft hav- 65 ing a slide bolt engageable with said cam-actuated lever, and means actuated by shift of said cam shaft in one direction to engage said bolt with said lever, and to free said bolt from said lever by reverse shift of said cam 70 shaft.

13. In a full-fashioned knitting machine, a loop regulating mechanism comprising a needle-bar, a loop-regulating shaft operatively connected to the latter, a longitudinally shiftable cam shaft having a loop-regulating cam fixed thereto, and a cam-actuated lever nor- 75 mally loosely carried by said loop-regulating shaft; a fixed member on said shaft and a frame-secured member associated with said 80 cam actuated lever, and means actuated by shift of said cam shaft to lock said lever to one of said members.

14. In a loop regulating mechanism for full-fashioned knitting machines comprising a longitudinally shiftable cam shaft having a cam thereon, and a loop regulating shaft having a cam engaging lever loosely mounted thereon, a fixed collar on said shaft and a frame-secured bracket associated with said 85 lever and having slide bolt sections normally aligned with a bolt section carried by said cam engaging lever, and means operated by reverse shifts of said cam shaft to move said bolt sections to engage said lever with said 90 collar or with said bracket.

15. In a full-fashioned knitting machine, a loop regulating mechanism comprising a needle-bar, a loop-regulating shaft operatively connected to the latter, a longitudinally shift- 100 able cam shaft having a loop-regulating cam fixed thereto, a cam-actuated lever loosely mounted on said loop-regulating shaft, a fixed collar on the latter carrying locking means engageable and disengageable with said cam actuated lever, and means carried by said cam shaft and shiftable with the latter to engage and disengage said locking means.

In testimony whereof I affix my signature.
CHRISTIAN F. MEYER.
